UNITED STATES PATENT OFFICE.

LOUIS SHOLES, OF MILWAUKEE, WISCONSIN, ASSIGNOR TO C. LATHAM
SHOLES TYPEWRITER MANUFACTURING COMPANY, OF MILWAU-
KEE, WISCONSIN, A CORPORATION OF WISCONSIN.

TYPE-WRITING MACHINE.

SPECIFICATION forming part of Letters Patent No. 698,749, dated April 29, 1902.

Application filed May 10, 1901. Serial No. 59,577. (No model.)

To all whom it may concern:

Be it known that I, LOUIS SHOLES, a citizen of the United States, residing at Milwaukee, in the county of Milwaukee and State of Wisconsin, have invented certain new and useful Improvements in Type-Writing Machines, of which the following is a specification, reference being had to the accompanying drawings, forming a part thereof.

10 My invention relates to type-writers of the class shown in United States Letters Patent Nos. 464,902 and 464,903, dated December 8, 1891, in which the type-bars have horizontal arms journaled parallel with each other and 15 movable endwise in suitable fixed bearings and transverse type-bearing arms which are brought by the endwise movement of the horizontal arms to a common plane and swung in that plane against the platen by turning 20 the horizontal arms.

The main objects of the invention are to make the type-bar-operating slides and their connections easily accessible and removable for inspection and repair, to simplify and improve 25 the construction of the slotted guide-plate, to effectively arrange the requisite number of type-bar-operating slides in a small space, to vary the leverage of the operating-slides on the type-bars according to 30 the different lengths of the type-bearing arms, to vary the leverage of the key-levers on said slides according to the extent of their movements, so as to secure a uniform degree of depression for all the keys, and generally 35 to improve the construction and operation of machines of this class.

The invention consists of certain novel features in the construction, arrangement, and combination of parts, as hereinafter particularly described, and pointed out in the claims.

In the accompanying drawings like letters designate the same parts in the several figures.

Figure 1 is a vertical longitudinal section 45 on the line 1 1, Fig. 3, of a portion of a type-writing machine embodying my improvements. Fig. 2 is a vertical cross-section on the line 2 2, Fig. 3; and Fig. 3 is a partial plan view and horizontal section on the line 50 3 3, Fig. 2.

A A are L-shaped or angular type-bars, each having a pivot-arm *a* and a type-arm *a'* at right angles thereto. The pivot-arms *a*, which are supported horizontally and parallel with each other in bearings B B, provided in 55 the frame, are capable of turning and moving endwise in said bearings. They are provided on opposite sides with pins or fingers *c* and *d*. The type-arms *a'*, which are provided with the characters or type, are of different lengths, as shown in Fig. 1, according to the distance of the pivot-arms *a* from the platen, which is indicated by a dotted line in Fig. 1, and they stand when at rest one above another in a plane perpendicular to 65 the axis of the platen and a little to one side of the common printing-point.

C is a guide and cover plate detachably fixed to the frame of the machine in front of and parallel with the pivot-arms *a*. It is 70 formed with an oblique series of L-shaped or angular slots *c'*, which engage with the forwardly-projecting fingers *c*. The horizontal parts of these slots are arranged directly opposite the pivot-arms *a*, with whose fingers *c* 75 they engage, so that said fingers will stand horizontally, as shown in Fig. 1, when the type-bars are at rest in their normal positions. This arrangement of the slots in the guide-plate with reference to the pivot-arms avoids 80 the necessity of forming the horizontal parts of said slots with beveled edges, as shown in each of the patents hereinbefore mentioned, and admits of punching and completely forming each slot in a single operation, thereby 85 greatly simplifying the construction of the guide-plate and materially reducing its cost. The guide-plate C serves to cover and protect the pivot-arms and bearings of the type-bars and to give a finished appearance to the 90 front of the machine.

D D are vertically-movable slides having oblique slots *d* *d'* engaging with the rearwardly-projecting fingers *d* *d*'. They are arranged in different planes in an accessible 95 position on the rear side of a back plate or frame E, which is attached to the machine-frame behind the pivot-arms *a*, and they are detachably connected with said plate and guided parallel therewith by shouldered turn- 100

buttons F, which are swiveled in said back plate and adapted to be engaged with longitudinal slots f in said slides, as shown in Fig. 1. They are held in place at their lower ends, 5 which are made narrower than their upper slotted portions, by a cross plate or bar G, the guiding-openings in which are arranged at different distances from the plane of the back plate D, as shown in Fig. 3. The slides 10 which are farthest from the back plate are connected with the type-bars which have the longest type-arms, and consequently require the most power for their operation. This arrangement of the slides also admits of their 15 overlapping one another, as shown in Fig. 2, and thus being contained within a small space, as well as affording means of varying the leverage of the operating connections with the type-bars according to the length of their 20 type-arms and the power required to operate them.

By turning the cross-bars of the buttons F into a vertical position the slides D can be readily removed and replaced, and by removing 25 the guide-plate C the pivot-arms a and their bearings become accessible and the type-bars may be removed. Inspection and repair of the machine are thus greatly facilitated.

H H are the type-levers, which are provided 30 at their front ends in the usual way with keys h h and are fulcrumed at their rear ends on a cross-rod I.

J J are intermediate or auxiliary levers arranged above the type-levers H and fulcrumed at their front ends on a cross-rod K. At their rear ends they are loosely engaged 35 with the lower ends of the slides D below the guide-plate G, and at intermediate points between the rod K and the slides D they are 40 connected with the type-levers by links j j.

It will be seen that the type-levers H are of the second class and the levers J are of the third class and that by connecting the links j with the levers J at different distances from 45 their fulcrums the leverage between the operating-keys and the type-arms may be adjusted to compensate for the greater movement of the slides, which are connected with and operate the longer type-arms, and to 50 provide for a like depression of all the keys for the operation of type-arms of different lengths.

The key-levers and the type-bars, with their connections, are returned to and held in their 55 normal positions by adjustable springs L. (Shown in Fig. 1.) The tension of these springs is adjusted by screws l l.

Type-writing machines of the class to which my improvements relate are usually each provided with two series of type-bars arranged 60 on opposite sides of the center of the machine with the type-arms a' at the inner ends of the pivot-arms a, and the guiding and operating connections of both series are alike, except 65 that the angular guiding-slots c' and the oblique slots d' in the slides are reversed on one

side of the machine with respect to those on the opposite side.

Various changes in the minor details of construction and arrangement of parts may be 70 made within the spirit and intended scope of my invention.

I claim—

1. In a type-writing machine the combination of a series of angular type-bars having 75 pivot-arms which are capable of turning and moving endwise, each of said arms being provided on opposite sides with fingers, a fixed guide-plate having a series of angular slots with which the fingers on one side of said 80 arms engage, and slides having oblique slots engaging the fingers on the opposite side of said arms, substantially as described.

2. In a type-writing machine the combination of a series of angular type-bars having 85 pivot-arms capable of turning and moving endwise and provided with fingers, a guide-plate having a series of angular slots engaging fingers on said arms, and a series of slides arranged in planes at different distances from 90 said arms and provided with oblique slots engaging fingers on said arms, substantially as described.

3. In a type-writing machine the combination of a series of angular type-bars having 95 pivot-arms capable of turning and moving endwise and provided with fingers, a fixed plate or frame parallel with said pivot-arms, and overlapping slides detachably connected with said plate in different planes and provided with cam-slots engaging said fingers, substantially as described.

4. In a type-writing machine the combination of angular type-bars having pivot-arms capable of turning and moving endwise and provided with fingers, a fixed plate or frame parallel with said arms and having openings through which said fingers project, and slides having oblique slots which engage said fingers and detachably connected with said plate 105 and guided by turn-buttons which engage longitudinal slots in said slides, substantially as described.

5. In a type-writing machine the combination of angular type-bars having pivot-arms 115 capable of turning and moving endwise and provided on opposite sides with fingers, a front plate having angular slots engaging the fingers on one side of said arms, a back plate having openings through which the fingers 120 on the opposite side of said arms project, and slides arranged in different planes on the rear side of said back plate and having oblique slots engaging with the rearwardly-projecting fingers of said arms, substantially as described.

6. In a type-writing machine the combination of a series of angular type-bars having 125 type-arms of different lengths and pivot-arms capable of turning and moving endwise and provided on opposite sides with fingers, a guide-plate arranged in front of and parallel 130

- with said arms and having angular slots engaging with the forwardly-projecting fingers, a back plate arranged behind and parallel with said arms and having openings through 5 which the rearwardly-projecting fingers thereof project, and slides detachably connected with said back plate and held and guided in different parallel planes by shouldered turn-buttons swiveled in said back plate and engaging 10 longitudinal slots in said slides, which are also provided with oblique slots engaging the rearwardly-projecting fingers of said pivot-arms, substantially as described.
7. In a type-writing machine the combination of angular type-bars having type-arms of different lengths and pivot-arms capable of turning and moving endwise and provided with forwardly-projecting fingers, a guide-plate having angular slots, the horizontal portions of which are directly opposite said pivot-arms, whose fingers engage therewith, and means for turning each pivot-arm and mov- 15 ing it endwise to produce an impression on the platen of the character with which the corresponding type-arm is provided, substantially as described. 25
8. In a type-writing machine the combination of angular type-bars having type-arms of different lengths and pivot-arms capable of turning and moving endwise and provided with fingers, slides arranged at different distances from said pivot-arms and having oblique slots engaging with said fingers, key-levers and auxiliary levers connected with said slides and at different distances from 30 their fulcrums with said key-levers, substantially as described. 35
- In witness whereof I hereto affix my signature in presence of two witnesses.
- LOUIS SHOLES.
